Des. 241,462

Patented Sept. 14, 1976

241,462

FLOWER POT

Frank T. Criscitello, Jr., 1086 Prospect Ave.,
Mountainside, N.J. 07042

Filed Jan. 21, 1976, Ser. No. 631,046

Term of patent 14 years

Int. Cl. D11—02

U.S. CL. D11—152

FIG. 1

FIG. 2

FIG. 3

FIG. 4

FIG. 5

FIG. 1 is a front elevation of a flower pot, incorporating my new design, which is identical to the rear elevational view and right and left side elevational views thereof.

FIG. 2 is an enlarged top plan view thereof;

FIG. 3 is an enlarged bottom plan view thereof.

FIG. 4 is a perspective view taken from the top left thereof.

FIG. 5 is a perspective view taken from the bottom right thereof.

I claim:

The ornamental design for a flower pot, as shown and described.
